(57) **CLAIM**

The ornamental design for a switch, as shown and described.

DESCRIPTION

FIG. 1 is a perspective view of an embodiment of a switch according to our new design;

FIG. 2 is a rear view of the switch of FIG. 1;

FIG. 3 is a front view of switch of FIG. 1;

FIG. 4 is a top view of the switch of FIG. 1;

FIG. 5 is a bottom view of the switch of FIG. 1;

FIG. 6 is a side view of the switch of FIG. 1; and,

FIG. 7 is an opposite side view of the switch of FIG. 1.

In these designs, any elements shown in broken lines form no part of the illustrated designs.
